UNITED STATES PATENT OFFICE

ALFRED C. GILBERT, OF HAMDEN, CONNECTICUT, ASSIGNOR, BY MESNE ASSIGNMENTS,
TO THE A. C. GILBERT COMPANY, OF NEW HAVEN, CONNECTICUT, A CORPORATION
OF MARYLAND

CONSTRUCTION TOY

Application filed June 7, 1927. Serial No. 197,141.

This invention relates to construction toys and more particularly to certain structural units or elements, such as strips, curved plates, perforated disks and flanged rings, each having perforations disposed therein to receive securing means, whereby these parts may be detachably assembled together and to other toy construction elements in various relations to form a variety of structural toy models.

The principal object of this invention is to provide a construction element susceptible of a variety of uses, whereby the number of different parts in a toy of this type will be maintained at a minimum.

Another object of this invention is to provide a number of such structural elements which may be secured together in various relations to form different toy structures or units thereof.

Still another object of this invention is to provide a flanged disk, having in its structure a plurality of structural elements each of which is adapted for use in various relations with one or more of the others, to form various toy structures or units thereof.

A further object of this invention is to provide a cylindrical structure, generally tubular in form, one end of which is closed by a built up head portion, said structure having as parts thereof construction toy elements which are adapted for use in various relations with other toy elements to produce other and differently formed structures.

To these and other ends, the invention consists in the novel features and combinations of parts to be hereinafter described and claimed.

In the accompanying drawings:

Fig. 1 is a perspective view of a toy steam engine in the structure of which are toy elements and units embodying the features of my invention;

Fig. 2 is a top plan view of the same;

Fig. 3 is a section on line 3—3 of Fig. 1;

Fig. 4 is an enlarged section of the upper part of this toy, taken on line 4—4 of Fig. 2;

Fig. 5 is a partial side view of another toy device illustrating another use for certain of

the toy elements embodying the features of my invention;

Fig. 6 is a section on line 6—6 of Fig. 5;

Fig. 7, 8 and 9 are perspective detail views of toy elements embodying the features of my invention, and which are adapted for use in forming various toys by assembling the same to other toy elements in various relations;

Fig. 10 is a partial view of part of another toy, in which an element of my invention is used in combination with other toy elements; and

Fig. 11 is a detail view of a toy element used in combination with the toy elements of this invention.

The toy steam engine illustrated in Figs. 1 to 4 inclusive, and the toys partially shown in Figs. 5, 6 and 10, have included in their structure toy elements which embody the features of my invention. In the steam engine of Figs. 1 to 4 inclusive, a boiler 10 is in the form of a cylindrical member having one end closed by an assembly of a ring 11, having a flange 12, and a perforated disk 13, the body portion of the cylindrical member being composed of a variety of curved plates 14. The flange ring 11 is also used in this model as a fly wheel, the spokes of which are produced by the use of strips 15, having equally spaced apart perforations 16 therein, and a hub therefor in the form of a bushed disk 17, provided with perforations 18, which are disposed about the same adjacent the periphery thereof.

In the toy illustrated in Figs. 5 and 6, the flanged ring 11 is used as a bull ring and supports a mast 19, and a swinging boom 20. In this toy, the disk 13 is also used, being assembled to the ring 11 in the same manner as in the steam engine of Figs. 1 to 4 inclusive. A bushed disk 21, having equally spaced perforations 22, disposed about the same, adjacent the periphery thereof, is secured to the disk 13 with the bushing 23 extending downwardly therefrom to form a part of a pivotal support therefor. The bushing 23 is provided with a shoulder 24, which is adapted to rest upon the upper flat surface of a toy element or mast step 25, the re-

duced end 26 of the bushing being rotatably received in an opening 27 therein. In Fig. 10, the disk 13 is used to support toy elements or flanged strips 28, to form a part of a toy such as a windmill. A bushed disk 17 similar to the one used in the steam engine of Figs. 1 to 4 inclusive, is used as the hub-member for this toy unit.

The ring 11 is provided with equally spaced apart perforations 29, disposed in a circular series adjacent its inner peripheral edge 30, each being spaced therefrom an amount substantially equal to or a multiple of the spacing between perforations in other toy elements, such as the perforated strips 15 and 31. The peripheral flange 12 of the ring 11 is provided with equally spaced apart perforations 32, disposed adjacent its free edge 33, each being spaced therefrom an amount substantially equal to or a multiple of the spacing in other toy elements, and in this instance, an amount substantially equal to the spacing between the perforations 29 and the edge 30 of the ring 11. The perforations 29 and 32 in the ring and flange respectively, are in alignment radially with respect to the axis of the ring. The ring 11 and flange 12 are, in this instance, formed integrally from one piece of flat material. A belt groove 34 is produced in the periphery of the flanged ring 11 during the formation thereof. The belt groove 34 is, in this instance, disposed closely adjacent the periphery of the ring 11, and in the flange edge adjacent the ring. The belt groove 34 is formed by bending the material of this element over and inwardly upon the ring 11, and then returning it outwardly and merging it into the flange 12.

The disk 13 is provided with a circular series of equally spaced apart perforations 35, each of which is spaced from the periphery of the disk substantially an amount equal to or a multiple of the spacing between perforations in other toy elements, and in this instance, an amount equal to the spacing of the perforations 29 from the edge 30 of the ring 11. The perforations 35 are disposed in the disk 13, so as to be in alignment radially with the perforations 29 in the ring 11. Each of the perforations 35 is one of a series of radially extending and aligned perforations, consisting, in this instance, of a circular series of elongated openings 36, a circular series of perforations 37, and a perforation 38. The perforations 35, 36 and 37 are spaced apart radially an amount substantially equal to or a multiple of the spacing between perforations in other toy elements, such as the strips 15 or 31, or the flanged strips 28. The perforation 38 is disposed substantially at the center of disk 13 and is of a diameter of sufficient size to receive the bushings of the bushed disks 17 and 21. The circular series of perforations 37 are so arranged that they

will correspond with the perforations 18 and 22 respectively of these bushed disks.

The curved plate 14 is produced from a flat piece of material, which is perforated as desired and then curved in a suitable die 70 whereby two curved or arcuate edges 39 and 39^a are formed, the ends of which are joined together by straight edges 40 and 41. The edges 40 and 41 are parallel and a series of perforations 42, each of which is elongated peripherally with respect to the curve of the plate, are provided adjacent each of the edges 40 or 41, and are at substantially right angles thereto. Intermediate the edges 40 and 41 and adjacent each of the curved edges 39 and 39^a, a circular perforation 50 is provided which is disposed in alignment with the perforation 42 of the series adjacent each of the straight edges. The peripheral spacing between the perforation 42 and the perforation 50 is substantially equal to the peripheral spacing of the perforations 32 of the flange 12.

The mast step 25 is produced from a strip of sheet metal, and comprises a flat top portion 43 having leg portions 44 at each end 90 thereof and disposed substantially at right angles thereto. Extending outwardly from and at substantially right angles to each of the leg portions 44 is a foot portion 45. A perforation 46 is provided in each of the foot portions 45, and a perforation 47 is provided in each of the leg portions 44. The perforation 27, disposed in the top portion 43 is of a diameter of sufficient size to receive the reduced end 26 of the bushing 23, associated 100 with the disk 21. The perforations 46 are spaced apart an amount which is a multiple of the spacing between perforations in other toy elements, such as those in the base plate 48.

A cylindrical member simulating a boiler 105 in Figs. 1 to 4 inclusive, is made up of a set or plurality, in this instance four, of plates 14, which are overlapped at the straight edges thereof, being secured together by means of bolts 49 which pass through the corresponding perforations 42. This set of plates is secured to another set of plates by overlapping the curved ends of each set, and securing them together by means of bolts 49, which pass through corresponding perforations 42 110 and 50 in the plates of each set. The upper curved ends of the upper set of plates is embraced by the flange 12, depending from the ring 11, and are secured thereto by means of bolts 49, which pass through the perforations 42 115 and 50 of the plates and corresponding perforations 32 of the flange 12. The upper end of the cylindrical or boiler shaped toy unit is covered partially by the ring 11, and more completely by the disk 13, which is disposed within the central opening of the ring, and embraced by the internal peripheral edge 30 thereof, whereby the disk 13 is flush with the ring 11. The disk 13 is secured to the ring 11 by means of the strips 31, and bolts 49, which 120

125

130

pass through the perforations in this strip which correspond with the perforations 35 in the disk 13, and 29 in the ring 11. A bolt 51 passing downwardly through an element or toy stack 52, and a washer 53, disposed from the opening 38 in the disk 13, secure the stack 52 to the disk.

The flanged ring 11, when used as a toy unit simulating a fly wheel, may be mounted upon a suitably supported shaft 54 and rotated by means of a motor 55. The motor 55 may be drivingly connected to the toy unit or fly wheel model by means of the belt 56, which rides in the groove 34 and over a suitable pulley 57 secured to the motor armature shaft 58. A similar use for the flange ring 11 is shown in Figs. 5 and 6, referred to above. In this instance, the toy unit simulating a bull ring for use in a toy such as a swingable boom hoist or the like, is rotatable by means of the belt 59, which rides in the groove 34 and over a pulley 60, which is rotatable by means of a crank 61. The toy unit or bull ring is in the form of a flanged disk, composed of the ring 11 and the disk 13 with which other toy elements may be readily associated or secured by means of bolts or other toy elements, such as angle pieces 62, bushed disks 21, and mast steps 25, which may be secured to the disk portion 13 by means of bolts 49 passing through corresponding perforations provided in each element.

In the toy illustrated in Figs. 1 to 4 inclusive, a cylindrical member or boiler 10 is secured to the base plate 48 by the use of angle pieces 62 and bolts 49, which pass through corresponding openings in both the corresponding perforations, in both the angle piece and the base plate. The frame-work of the motor 55 is provided with foot pieces 63, each of which is provided with an opening in the form of a slot 64. The openings 64 are each spaced from the other an amount equal to or a multiple of the spacing of perforations in other elements of the toy, such as the base plate 48 and strips 65 upon which the motor is mounted.

While I have shown and described a preferred embodiment of my invention, it will be understood that the same is not to be limited to the details shown but is capable of modification and variation which will lie within the spirit of the invention and the scope of the appended claims.

55 What I claim is:

1. A toy unit, composed of a plurality of toy elements, one of said elements comprising a ring having a flange extending at an angle from and about the periphery thereof, and a disk disposed within the opening formed by the internal periphery of said ring to substantially close the same.
2. In a toy unit, a ring-shaped element, and a disk, said disk being disposed in the opening formed by the internal periphery of
3. In a toy unit, a ring-shaped element having a disk secured thereto, with the peripheral edge of said disk disposed closely adjacent to the internal peripheral edge of said ring.
4. A toy unit, composed of a plurality of toy elements, one of said elements comprising a ring having a flange extending at an angle from and about the periphery thereof, said flange having a groove extending peripherally thereabout, and a disk disposed within the opening formed by the internal periphery of said ring, and a plurality of curved plates secured to said flange in such a manner as to form a cylinder.
5. In a toy unit, a ring-shaped element having a disk secured thereto, with the peripheral edge of said disk disposed adjacent to the internal peripheral edge of said ring; and a cylindrically-shaped member extending substantially at right angles from the external periphery of said ring.
6. In a toy unit, a ring-shaped element having a disk secured thereto, with the peripheral edge of said disk disposed adjacent to the internal peripheral edge of said ring, and a cylindrically-shaped member extending substantially at right angles from the external periphery of said ring, said member comprising a plurality of curved plates secured together and to said ring.
7. In a toy unit, a ring-shaped element and a disk, said disk being disposed in the opening formed by the internal periphery of said ring, and with its upper surface substantially flush with the upper surface of said ring, and a cylindrically-shaped member extending substantially at right angles from the external periphery of said ring.
8. A toy unit, composed of a plurality of toy elements, one of said elements comprising a ring having a flange extending at an angle from and about the periphery thereof, and a disk disposed within the opening formed by the internal periphery of said ring, the external edge of said disk engaging the edge about the opening in said ring.
9. In a toy unit, a ring shaped element having a disk secured thereto, with the peripheral edge of said disk disposed closely adjacent the internal peripheral edge of said ring, said disk and said ring being disposed in the same plane.
10. A toy unit, composed of a plurality of toy elements, one of said elements comprising a ring having a flange extending at an angle from and about the periphery thereof, and a disk disposed within the opening formed by the internal periphery of said ring, and a plurality of curved plates secured to said flange in such a manner as to form a cylinder.

11. In a construction toy, a wheel-like element formed of sheet material and comprising a flat annular portion having its peripheral edge turned over upon itself in engagement therewith and extending radially inwardly thereover to provide a double thickness of material thereat, and then bent upon a curve to form a belt groove closely adjacent said edge, said edge being extended axially 10 beyond said belt groove and away from said disk portion to form an axially directed flange portion, said flange having perforations therein for the attachment of other parts.
- 15 12. In a toy unit, a ring-shaped element and a flat disk, said disk being disposed in and substantially filling the opening formed by the internal periphery of said ring and having a series of radially disposed and spaced apart 20 perforations therein, said ring-shaped element having a perforation therein in radial alignment with the perforations in said disk.
13. In a toy unit, a ring-shaped element and a flat disk, said disk being disposed in 25 and substantially filling the opening formed by the internal periphery of said ring and having a plurality of peripherally spaced apart series of radially disposed perforations therein, said ring having a series of 30 peripherally spaced apart perforations, each perforation of which is in radial alignment with the perforations in one of the series of perforations disposed in said disk.
14. In a toy unit, a ring-shaped element 35 having a flange extending axially therefrom and disposed substantially about its periphery, and a plurality of curved plates disposed adjacent one another about said flange and extending axially therefrom, each of said 40 plates having axially spaced apart and circumferentially elongated perforations in each side edge thereof, coinciding with corresponding perforations in the adjacent edge of the adjacent plates to receive fastening members and to permit circumferential adjustment of one plate relatively to the other, and a disk secured to said ring-shaped element with the peripheral edge of said disk disposed closely adjacent to the internal peripheral 50 edge of said element.
15. A toy unit, composed of a plurality of toy elements, one of said elements comprising a ring having a flange extending at an angle from and about the periphery thereof, and a disk disposed within and substantially filling the opening formed by the internal periphery of said ring, and a shaft receiving member secured to said disk substantially at the center thereof.
- 55 60 60 In witness whereof, I have hereunto set my hand this 2d day of June, 1927.

ALFRED C. GILBERT.
